US0D1059626S

(12) **United States Design Patent** (10) **Patent No.:** **US D1,059,626 S**
(45) **Date of Patent:** **** Jan. 28, 2025**

(54) **DIAGNOSTIC EQUIPMENT**

(71) Applicant: **HI TECHNOLOGIES LTDA**, Curitiba (BR)

(72) Inventors: **Claudiane Isabel Franco Araujo**, Curitiba (BR); **Victor Henrique Alves Ribeiro**, Curitiba (BR); **Evair Borges Severo**, Curitiba (BR); **Guilherme Calesco Avanço Rodrigues**, Curitiba (BR); **João Victor Predebon**, Curitiba (BR); **Marcus Vinicius Mazega Figueiredo**, Curitiba (BR); **Sérgio Renato Rogal, Jr.**, Curitiba (BR); **Marcelo Júnior Cossetin**, Curitiba (BR); **Luis Felipe Hartman**, Curitiba (BR); **Adriano Artur Timm**, Curitiba (BR); **Ivan Lucas Reis Silva**, Curitiba (BR); **Flávia Zhu Teng**, Curitiba (BR); **Ricardo Gurgel De Sousa**, Curitiba (BR); **Erika Santiago**, Curitiba (BR); **Aléxia Thamara Gasparin**, Curitiba (BR)

(73) Assignee: **HI TECHNOLOGIES LTDA**, Curitiba (BR)

(**) Term: **15 Years**

(21) Appl. No.: **29/830,773**

(22) Filed: **Mar. 15, 2022**

(51) LOC (15) Cl. **24-02**

(52) U.S. Cl.

USPC **D24/216**

(58) **Field of Classification Search**

USPC D24/107, 108, 186, 216, 223, 224, 231, D24/232

(57) **CLAIM**

The ornamental design for a diagnostic equipment as shown and described.

DESCRIPTION

FIG. 1 is a perspective view of a diagnostic equipment showing our design.

FIG. 2 is a front elevation view thereof.

FIG. 3 is a bottom perspective view thereof.

FIG. 4 is a first side elevation view thereof.

FIG. 5 is a second side elevation view thereof.

FIG. 6 is a top plan view thereof; and,

FIG. 7 is a bottom plan view hereof.

(Continued)

The diagnostic equipment is useable in testing of biological samples.

In the drawings, the equal-length broken lines depict portions of the diagnostic equipment that form no part of the claimed design.

1 Claim, 7 Drawing Sheets
